DESIGN FOR A LIGHTER OR SIMILAR ARTICLE

Arthur Pantzer, New York, N. Y.

Application May 28, 1945, Serial No. 119,778

Term of patent 7 years

(Cl. D48—27)

To all whom it may concern:

Be it known that I, Arthur Pantzer, a citizen of the United States, residing at New York, in the county of New York and State of New York, have invented a new, original, and ornamental Design for a Lighter or Similar Article, of which the following is a specification, reference being had to the accompanying drawing, forming part thereof.

Fig. 1 is a perspective side and rear view of the lighter showing my new design, and

Fig. 2 is a perspective side and front view of the lighter shown in Fig. 1.

I claim:

The ornamental design for a lighter or similar article, substantially as shown.

ARTHUR PANTZER.
